UNITED STATES PATENT OFFICE.

WILLIAM E. CHRISTMAN AND ROY L. WARREN, OF PHILADELPHIA, PENNSYLVANIA,
ASSIGNORS, BY MESNE ASSIGNMENTS, TO J. MAURICE KELLEY, OF PHILADELPHIA,
PENNSYLVANIA.

COVER-APPLYING DIE CONSTRUCTION.

Application filed January 5, 1924. Serial No. 684,673.

To all whom it may concern:

Be it known that we, WILLIAM E. CHRISTMAN and ROY L. WARREN, citizens of the United States, residing at Philadelphia, in the county of Philadelphia and State of Pennsylvania, have invented certain new and useful Improvements in Cover-Applying Die Construction, of which the following is a specification.

One object of our invention is to provide improved means for securely, quickly and neatly applying various portions of covers to cases and particularly to eye-glass cases which are usually made of sheet metal and of a shape difficult to properly cover.

Another object is to so construct our invention that it will be capable of covering such cases with leather, imitation leather and various forms of processed cloth which are ordinarily difficult to apply as covers to eye-glass cases.

The above mentioned objects and other advantageous ends which will be described hereinafter, we attain in the following manner, reference being had to the accompanying drawings in which

Figure 1 is a front elevation showing one set of said series of dies,

Figure 2 is a sectional plan view taken on the line 2-2 of Figure 1,

Figure 3 is a transverse sectional view taken on the line 3-3 of Figure 1,

Figure 4 is a bottom view of the top die shown in Figures 1, 2 and 3, and

Figures 5 to 7 inclusive are perspective views showing the various steps in the covering operation effected by the construction illustrated.

Referring to the drawings, a press stand 25 has a base 26 from the rear of which projects a standard 27. The standard 27 has a head 28 provided with a vertical bore 29 in which slides a plunger 30. A shaft 31 is journaled in said standard and has a pinion 32 thereon which meshes with a rack 32 on the plunger 30. A hand-lever 33 is secured to the shaft 31 and is capable of being swung to effect the raising and lowering of the plunger 30. The plunger 30 carries a rod 34 which extends upward through said plunger and is provided at its top with a handle 35. The lower end of the rod 34 is screw threaded and extends through an electric heating element 36 into a die 37, the

arrangement being such that the electric heating element is clamped between the die 37 and the lower end of the plunger 30. The electric heating element can be of any type heated by electric resistance and as illustrated, electric current is supplied by a wire 38 as shown in Figure 1. It may be here stated that the die 37 can be raised or lowered by the swinging of the lever 33. A die block 39 rests upon the top surface of the base 26 and has two notched extensions 40 through which stud bolts 41 extend, said stud bolts being screwed into the base 26 and extending through the notches of the extensions 40 so as to clamp the die block 39 to the base directly under the die 37. The die block 39 is cut out as shown at 42 to provide a chamber for a movable base die 43. This base die has a depending post 44 which slidably fits in a bore 45 extending vertically through the die block 39 as clearly shown in Figure 3. Coiled springs 46 are positioned between the bottom of the base die 43 and the bottom of the chamber 42, said springs being operative to raise said base die into the position shown in Figure 3 and under certain conditions being compressed to allow the base die 43 to be lowered. The chamber 42 is curved at its opposite ends to provide curved walls 47. It may be here stated that the dies as illustrated are shaped to cover an eye-glass case of the shape shown in Figure 5 of the drawings. The chamber 42 is open at its front and includes a rear wall 48 and it will be noted that the end walls 47 and back wall 48 produce a guideway for the base die 43 during its movement as will be hereinafter described. The post 44 has a notch 49 which when the base die is lowered, is adapted to be engaged by a latch 50. The latch 50 is slidably mounted in the die block 39 and is pivotally connected at its outer end to a lever 51. The lever 51 is pivotally supported at 52 in front of the die block and has a finger-engaging portion 53 which is backed by a spring 54, 100 said spring being operative to move the latch 50 inward when the base die 43 is lowered so that the inner end of the latch 50 will engage in the notch 49 and thereby hold the base die 43 down. It will be noted, 105 however, that considering that the die 37 is raised, if the portion 53 of the lever 51 is pushed toward the die block, the latch 50

will be withdrawn from the notch 49 and the springs 46 will move the base die 43 upward. The upward movement of the base die is arrested by a disk 55 on the post 44, said disk being of larger diameter than the bore 45. Thus the base die can only raise to the height shown in Figure 3.

The die block 39 is provided with two channels 56 and 57 to the rear of the chamber 42. These channels are cut in the top of said die block and form slide-ways for two bars 58 and 59. Two lateral plate dies 60 and 61 are slidably mounted on the top surface of the die block 39 and are secured respectively to the bars 58 and 59. These plate dies have operating edges 62 and 63 which correspond in shape to the end walls 47 of the chamber 42. The edges 62 and 63 intercept points 64 and 65 on the plate dies 60 and 61. Said pointed parts 64 and 65 are directly above pointed parts 66 and 67 of the die block 39. The upper surface of the plate dies 60 and 61 are preferably beveled or slightly rounded adjacent the edges 62 and 63 for a purpose hereinafter rendered obvious.

A lever 68 has a hub 69 which is pivotally mounted in a bore 70 in the die block 39, said bore at its top communicating with the channels 56 and 57. The hub 69 has a cam 71 at its top located between the inner ends of the bars 58 and 59. The bars 58 and 59 have screws 72 and 73 secured thereto and said screws extend outward through slots 74 and 75. A coiled spring 76 has its opposite ends secured to the springs 72 and 73 and is operative to move the bars 58 and 59 toward each other and consequently move the lateral plate dies 60 and 61 toward each other when permitted to do so by the cam 71. Figure 2 of the drawings shows the lever 68 in such a position that the cam 71 will hold the plate dies 60 and 61 apart against the action of the spring 76. However, if the lever 68 is swung toward the right, the cam 71 will move into such position as to allow the spring 76 to move the plate dies 60 and 61 slightly toward each other. A plate 77 is secured to the top of the die block 39 and serves to limit the movement of said plate dies 60 and 61 toward each other and also serves as a cover for the top of the bore 70 and the cam 71.

The die 37, as clearly shown in Figures 1 and 4, has rounded ends 78 adapted, when the plunger 30 moves downward, to enter the space between the end walls 47 of the chamber 42. Furthermore, said die 37 when moved downward will be operative to move said base die 43 downward as previously described, which action occurs during the application of a cover to a case as will be hereinafter specifically described. The die 37 has two fingers 79, the bottom surfaces 80 of which are positioned above the bottom sur-

face 81 of the main body 82 of said die 37. These fingers 79 are operative to assist in affixing parts of the cover to the pocket of the eye-glass case during one stage of the covering operation hereinafter described.

In Figure 5 we have shown an eye-glass case 136 which includes a body 137 and a lid 138, said lid being hinged at 139 to the body 137. The case is made of sheet metal and includes an overlaying flange 140 which provides a pocket of well known formation in the manufacture of eye-glass cases. A coiled spring 141 has one end secured to the lid and the other end secured to a looped anchoring member 142 in the body 137; the hinge 139 being discontinued at the place where the spring extends into the body. Said case is of a well known construction and the arrangement of the spring presents the advantage of holding the lid open when the lid is moved into a certain position and also for holding the lid closed after the lid has been moved past what is known as the dead center during the closing action. In Figure 5 we have shown a cover 143 in the form of a cut blank. This cover can be made of leather, imitation leather or processed cloth and the surface 144 is coated with glue capable of adhering to the surface of the case when heated and pressure is applied as will be more thoroughly comprehended in the following description.

In carrying out the covering operation of said case with the series of dies above described, the operator, while the base die 43 is held down by the latch 50, places the body 137 of the case within the chamber 42 so that the bottom of said body rests upon the top of the base die 43 with the pocket 140 of the case toward the rear. The lever 33 is then swung to move the die 37 downward into the body of the case and since said die 37 is heated, the heat will be transferred to the body of the case. The latch 50 is then released by pressing the portion 53 of the lever 51 and the lever 33 is then swung to raise the die 37; the springs 46 operating to raise the base die 43 into the position shown in Figures 1 and 3. The operator then removes the heated case and places it on the blank 115 cover in the position shown in Figure 5, the bottom of the body engaging the glued surface of the cover blank. The cover and the case so positioned thereon is then placed upon the top of the base die 43 and the top die 37 is moved downward into the body portion in the same manner as previously described. This action will cause the side flaps 145 and tab portions 146 to be bent upward against the outer end surfaces 147 of the body 137, the end walls 47 of the chamber 42 serving to press the parts 145 and 146 of the cover against the ends of the body 137. At the same time during said action, the base die 43 will be lowered and a stretch- 130

ing action of the cover across the bottom of the body 137 will be effected so as not to allow any wrinkles to exist and the action will result in a smooth firm application of the covering material to the bottom and outer ends of the body 137. The latch 50 will automatically move into the notch 49 to lock the base die 43 in its lowered position. The top die 37 is then raised and the lever 68 is swung to allow the lateral plate dies 60 and 61 to move toward each other and in so doing the edges 62 and 63 will bend the parts 145 and 146 inward over the top of the ends of the body 137 into the position clearly shown in Figure 6; the parts 146 being positioned over the top surface of the pocket flange 140 while the parts 145 extend over the space between the pocket and the rear of the body. The top die 37 is again moved downward into the body and during this action the fingers 79 will press the parts 146 into firm holding contact with the upper surface of the pocket flange 140 and the ends 78 of the die 37 will press the overhanging parts 145 into engagement with the inner surfaces of the ends of the body 137. Figure 7 of the drawings shows the cover after said latter part of the operation. The case is then removed from the die 43 and the remaining portions 148 and 150 of the cover can be applied to the case flange 140 and lid 138 by means not claimed in this application.

We have found that by heating the die structure and using glue which when heated will adhere to the cases, the covers will hold firmly to the cases. However if any other form of glue or paste is used which does not require to be heated in order to adhere to the cases, then it will be understood that it will be unnecessary to heat the dies.

Having thus described our invention what we claim as new and desire to secure by Letters Patent is:

1. In a cover-applying construction for cases of the character described, a series of dies including a die block having a chamber; a die movable within said chamber and upon which a cover with a superimposed case body can be positioned; a die movable relatively to said die block and operative to move said case body to cause said first die to move within the chamber and thereby effect the stretching of the cover over the bottom of the case body and the turning of portions of the cover upwardly against the outer side surfaces thereof; automatically operative means for holding said first die after said movement; transversely movable dies operative to bend said upwardly turned portions of the cover inwardly over the top edges of the case body, said second mentioned die being operative to move into the case body and

bend and press said inwardly bent portions of the cover into engagement with the inner side surfaces of the case body; and means for returning said first mentioned die to its normal position after its holding means is released.

2. In a cover-applying construction for an eye-glass case having a body with a pocket flange spaced above and overlaying the bottom of the body between flanged ends thereof, a series of dies including a die upon which a cover with said body thereon can be placed; dies for turning portions of said cover against the outer portions of said flanged ends and over the tops thereof and other portions over said pocket flange; and a die having a portion movable into the body and having parts operative to press said latter portions of the cover into engagement with said pocket flange.

3. In a cover-applying construction for cases of the character described, a series of dies including a die block having a chamber; a die slidably fitting said chamber and upon which a cover with a case superimposed can be positioned; a die movable relatively to said block and operative to move said case body to cause said first die to move downwardly in said chamber; spring means for moving said first die in an opposite direction; and an automatically operative latch for holding said first die against the movement of said spring means when the second mentioned die is raised.

4. In a cover-applying construction for cases of the character described, a series of dies including a die block having a chamber; a die slidably fitting said chamber and upon which a cover with a case superimposed can be positioned; a die movable relatively to said die block and operative to move said case body to cause said first die to move downwardly in said chamber; spring means for moving said first die in an opposite direction; a post on said first die having a notch; a latch; and automatically operative means for moving said latch into said notch to hold said first die against movement of said spring means.

5. In a cover-applying construction for cases, a series of dies including a die block having a die chamber; slidably mounted plate dies; spring means for moving said plate dies to overhang said chamber; and a pivoted lever having a cam operative to move said plate dies against the action of said spring means so as not to overhang said chamber.

In testimony whereof we have signed our names to this specification.

WILLIAM E. CHRISTMAN.
ROY L. WARREN.
